UNITED STATES PATENT OFFICE.

JOHN M. WEISS, OF NEW YORK, N. Y., AND CHARLES R. DOWNS, OF CLIFFSIDE, NEW JERSEY, ASSIGNEES TO THE BARRETT COMPANY, A CORPORATION OF NEW JERSEY.

PRODUCTION OF MALEIC ACID.

1,318,632.

Specification of Letters Patent. Patented Oct. 14, 1919.

No Drawing.

Application filed May 27, 1918. Serial No. 236,900.

To all whom it may concern:

Be it known that we, (1) JOHN M. WEISS and (2) CHARLES R. DOWNS, citizens of the United States, residing at (1) 210 West 110th street and (2) Cliffside, in the counties of (1) New York and (2) Bergen and States of (1) New York and (2) New Jersey, have invented certain new and useful Improvements in the Production of Maleic Acid, of 10 which the following is a specification.

This invention relates to the oxidation of aromatic hydrocarbons or their derivatives, whereby compounds of the straight chain or aliphatic series may be obtained.

15 More particularly our invention has for one of its objects the partial oxidation of a di-substitution product of a compound containing the benzene ring or nucleus in the presence of a suitable catalyst.

20 While our invention may be carried out with different compounds it will be specifically described in its operation as applied to the partial oxidation of quinone in the presence of a catalyst for the purpose of 25 forming maleic acid and formaldehyde.

We may form an intimate mixture of oxygen and of quinone (which has been produced in any suitable way, for example, in accordance with the process set forth in 30 our co-pending application Serial No. 236,899 filed May 27, 1918, and pass the same through a heated region such as the interior of hollow tubes which contains a proper catalyst such as, for example, vanadium 35 oxid, or other compounds of vanadium. The temperature should be maintained at about 300° C. to 700° C., and the pressure may vary from a partial vacuum to a pressure far above atmospheric, say up 40 to five atmospheres or more, while the mixture is in contact with the catalyst. The mixture may be injected into the heated space in the form of vapor or may be sprayed 45 therein, while the said space contains pumice or other porous material which may be im- 50 pregnated with the catalyst in order to promote proper contact. The oxygen may be in the pure state or may be oxygen of the air, or may be diluted with nitrogen or other 55 inactive diluents, which will exert a blanketing effect to assist in limiting or controlling the oxidation, and in preventing complete oxidation to the point of combustion.

The conditions under which the desired 55 reactions take place may be varied as by changing the length of time during which

the mixture is in transit through the reaction chamber, changing the temperature and pressure, varying the amounts of oxygen and the diluents in proportion to the quinone, etc.

We have obtained very satisfactory results by first mixing or dissolving the quinone in benzene (benzol C_6H_6) and thereafter introducing this mixture or solution with air into the reaction chamber and subsequently condensing the resulting products. While we do not wish to be understood as limiting our process to any particular theory as to the reaction which takes place, it seems from the results which we have obtained that probably the quinone already present is partially and selectively oxidized to form maleic acid and formaldehyde, while a portion of the benzene is also partially and selectively oxidized to produce a corresponding amount of quinone, and another portion of benzene is further oxidized to produce maleic acid and formaldehyde. That is, there may be a substantially constant proportion of quinone to maleic acid in the condensate when the process is operated under a fixed set of given conditions.

In the condensate is usually found quinone, maleic acid, excess benzene, formaldehyde, water and other by-products. The maleic acid may be permitted to crystallize out and be thus removed, or it may be removed by shaking the condensate with water. After the maleic acid has been removed, and also other products if necessary, the residual benzene-quinone solution is passed again with more benzene and oxygen through the reaction chamber in contact with the catalyst whereby more maleic acid is formed as above indicated without materially increasing the amount of quinone present.

It is, of course, obvious that the diluent gases present during the reaction, (and which may exert a blanketing influence to aid in preventing a complete oxidation to the point of combustion), will not be condensed, so far as they may be of a non-condensable character, but will pass off in a gaseous state, while the condensable products are condensed and collected.

From the foregoing description it will be noted that the process of the present invention may be considered, from one aspect, as a process of effecting a partial and selective oxidation of quinone to compounds of the

aliphatic series such as maleic acid and formaldehyde, while from another aspect the process of the invention may be considered a combination process for effecting a simultaneous oxidation of quinone to aliphatic compounds and the catalytic oxidation of benzene to quinone or part to quinone and part to other oxidation products, so that further amounts of quinone are formed 10 from benzene during the same procedure which results in the oxidation of quinone to aliphatic compounds.

It will be noted also that the process of the present invention can, with advantage, 15 be practised as a cyclic process with separation and return of the unchanged benzene and quinone to be further acted on, in the manner above described.

What I claim is:

20 1. The herein described process of oxidizing quinone in the vapor phase by an oxygen containing gas at such a temperature and pressure and in the presence of such a catalyst that maleic acid is produced, and recovering maleic acid from the products of reaction.

25 2. The herein described process of oxidizing quinone in the vapor phase by an oxygen containing gas at such a temperature and pressure and in the presence of vanadium 30 oxid as a catalyst so that maleic acid is produced, and recovering maleic acid from the products of reaction.

35 3. The herein described process of oxidizing quinone in the vapor phase by treating it with an oxygen containing gas at a temperature between 300° C. and 700° C. and at such a pressure and in the presence of such a catalyst that maleic acid is produced, and recovering maleic acid from the products of reaction.

40 4. The herein described process of oxidizing quinone in the vapor phase by treating it with an oxygen containing gas at a temperature between 300° and 700° C. in the presence of vanadium oxid as a catalyst so that maleic acid is produced, and recovering maleic acid from the products of reaction.

45 5. The herein described process of oxidizing a mixture of benzene and quinone in the vapor phase by an oxygen containing gas at such a temperature and pressure and in the presence of such a catalyst that maleic acid is produced, and recovering maleic acid from the products of reaction.

55 6. The herein described process of oxidizing a mixture of benzene and quinone in the vapor phase by an oxygen containing gas at such a temperature and pressure and in the presence of vanadium oxid as a catalyst so that maleic acid is produced, and recovering maleic acid from the products of reaction.

7. The herein described process of oxidizing a mixture of benzene and quinone in the vapor phase by treating it when an oxygen 65 containing gas at a temperature between 300° C. and 700° C. and at such a pressure and in the presence of such a catalyst that maleic acid is produced, and recovering maleic acid from the products of reaction. 70

8. The herein described process of oxidizing a mixture of benzene and quinone in the vapor phase by treating it with an oxygen containing gas at a temperature between 300° C. and 700° C. in the presence of 75 vanadium oxid as a catalyst so that maleic acid is produced, and recovering maleic acid from the products of reaction.

9. The herein described process of oxidizing a mixture of benzene and quinone in the 80 vapor phase by treating it with an oxygen containing gas at such a temperature and pressure and in the presence of such a catalyst that maleic acid is produced, separating the maleic acid and subjecting the residual benzene and quinone to further similar 85 oxidation to form further amounts of maleic acid.

10. The herein described process of oxidizing a mixture of benzene and quinone in the 90 vapor phase by treating it with an oxygen containing gas at such a temperature and pressure and in the presence of vanadium 95 oxid as a catalyst so that maleic acid is produced, separating the maleic acid and subjecting the residual benzene and quinone to further similar oxidation to form further amounts of maleic acid.

11. The herein described process of oxidizing a mixture of benzene and quinone in the 100 vapor phase by treating it with an oxygen containing gas at a temperature between 300° C. and 700° C. and at such a pressure and in the presence of such a catalyst that maleic acid is produced, separating the 105 maleic acid and subjecting the residual benzene and quinone to further similar oxidation to form further amounts of maleic acid.

12. The herein described process of oxidizing a mixture of benzene and quinone in the 110 vapor phase by treating it with an oxygen containing gas at a temperature between 300° C. and 700° C. and at such a pressure and in the presence of vanadium oxid as a catalyst so that maleic acid is produced, 115 separating the maleic acid and subjecting the residual benzene and quinone to further similar oxidation to form further amounts of maleic acid.

In testimony whereof we affix our signatures.

JOHN M. WEISS.
CHARLES R. DOWNS.
